[57] CLAIM

The ornamental design for a whirlpool spa tub, as shown and described.

DESCRIPTION

FIG. 1 is a perspective view of a whirlpool spa tub showing our new design;

FIG. 2 is a top-plan view thereof;

FIG. 3 is a cross-sectional view taken along line 3—3 of FIG. 1;

FIG. 4 is a cross-sectional view taken along line 4—4 of FIG. 1;

FIG. 5 is a cross-sectional view taken along line 5—5 of FIG. 1; and

FIG. 6 is a cross-sectional view taken along line 6—6 of FIG. 1.

The fragmentary broken line around FIG. 1 is for illustrative purposes only and forms no part of the claimed design.

FIG. 1

FIG. 2

FIG. 3

FIG. 4
